Primary Examiner — Rosemary K Tarcza*Assistant Examiner* — James Thorn, Sr.*(74) Attorney, Agent, or Firm* — Anna Vishev, Esq.(57) **CLAIM**

The ornamental design for an expandable drawer divider, as shown and described.

DESCRIPTION

FIG. 1 is a perspective view of the expandable drawer divider, according to the first embodiment of my new invention;

FIG. 2 is a front thereof, the rear being a mirror image of the front side;

FIG. 3 is a left side view thereof;

FIG. 4 is a right side view thereof;

FIG. 5 is a bottom plan view thereof;

FIG. 6 is a top plan view thereof;

FIG. 7 is a perspective view of the expandable drawer divider, according to the second embodiment of my new design;

FIG. 8 is a front view thereof, the rear side being a mirror of the front side;

FIG. 9 is a left side view thereof;

FIG. 10 is a right side view thereof;

FIG. 11 is a bottom plan view thereof; and,

FIG. 12 is a top plan view thereof.
